UNITED STATES PATENT OFFICE.

WILLIAM F. REACH, OF CHICOPEE, MASSACHUSETTS, ASSIGNOR TO A. G. SPALDING & BROS., OF JERSEY CITY, NEW JERSEY, A CORPORATION OF NEW JERSEY.

TUBULAR ICE-SKATE.

1,292,876.

Specification of Letters Patent. Patented Jan. 28, 1919.

Application filed September 18, 1918. Serial No. 254,583.

To all whom it may concern:

Be it known that I, WILLIAM F. REACH, a citizen of the United States, residing at Chicopee, Massachusetts, have invented certain new and useful Improvements in Tubular Ice-Skates, of which the following is a specification.

My invention relates to the general type of skates known as tubular and which are particularly adapted to withstand the severe strains in playing hockey and in use by athletes and the invention consists in the features or combination and arrangement of parts hereinafter described and particularly pointed out in the claims.

In the accompanying drawings:—

Figure 1 is a side view of the skate complete.

Fig. 2 is a plan view.

Fig. 3 is a sectional view on line 3—3 of Fig. 1.

Fig. 4 is a side view of the main tubular body member of the skate.

Fig. 5 is a plan view of the member shown in Fig. 4.

Fig. 6 is a side view of a post or supporting member for the heel plate.

Fig. 6^a is a vertical sectional view of the member of Fig. 6.

Fig. 6^b is a top plan view of the member of Fig. 6 and Fig. 6^c is bottom plan view of the member of Fig. 6.

Figs. 7, 7^a, 7^b, 7^c are views similar to Figs. 6 to 6^c but of a member which connects the sole plate with the main body member of the skate.

Figs. 8, 8^a, 8^b, 8^c are views similar to Figs. 6 to 6^c but of a supplemental member for connecting the foot plate with the main body member.

In these drawings the main body member 1 of the skate consists of a tube-like piece having depending flanges 2 embracing and secured to the runner 3.

This body member has its upper wall cut at 4 with the material around the cut raised to provide a wall 5 the contour of which, as viewed in plan, is of general elliptical form but differing from the shape of an ellipse mainly in that its sides are parallel. The end walls are slightly curved and convergent upwardly in respect to each other and the top edges of the sides are curved downwardly and merge into the upwardly curved edges of the end walls.

The sides of these attaching lugs or walls are raised in the planes of the sides of the tubular member and are therefore no wider than the said member but they are of greater extent lengthwise, than crosswise.

Over these lugs or projecting walls, posts or coupling pieces are placed for attaching and supporting the heel and toe plate to and upon the main tubular body of the skate. The heel plate coupling or supporting post 6 is shown in detail in Figs. 6 and 6^c and a description of this will also answer for the member shown in Figs. 7 to 7^c which attaches the rear part of the foot plate to and supports it on the main tubular body member 7 of the skate. This member viewed from the side is of the general form of an hour-glass being small at the middle region and flaring outwardly at top and bottom. Viewed in plan it is of general elliptical 75 form having flat sides. Its top edge is in one plane but slightly inclined downwardly from rear to front to suit the slight incline of the heel plate. Its bottom edge is rounded.

This post or coupling 6 is slipped over the projection 5 and is brazed thereto and its upper end receives within it the conical projection or wall depending from the heel plate to which it is brazed, this completing 85 the connection. The elongated form of the post as viewed in plan having its major axis extending longitudinally of the skate provides a strong construction to resist the strains and the fact that the wall of the 90 post finds a bracing around its entire circuit on the projecting wall or rim 5 also contributes to the strength of the connection, the said wall 5 rising from and extending, as described above, along both sides of the 95 body member of the skate and strength is also afforded in the post itself against stresses lengthwise of the skate and at angles thereto by the hour-glass shape presenting the principle of the arch at front and rear 100 to resist horizontal strains.

The post 7 for the foot plate as above stated is of similar construction to that just described and this post is arranged under the rear position of the foot plate where 105 most of the strain comes, i. e., about under the ball of the foot.

The forward post 8 need not be so strong as the posts 6 and 7 as it acts more in the nature of a tie piece or stay between the toe 110

portion of the foot plate and the body of the 5
skate and therefore this support is in the
form of a plain cylindrical tube having its
upper end cut off square and its lower end
formed on a curve and flared both forwardly
and backwardly but mostly at the front.

The upper end of this stay receives a plain
nipple from the foot plate and its lower end
receives a hollow projection 9 raised from
10 the tubular body of the skate. This stay is
slightly inclined backwardly and upwardly.

It will be understood that the disclosure
herein is to be regarded in an illustrative
and not in a restrictive sense, the scope of
15 the invention being defined by the appended
claims.

I claim:

1. A skate having its body consisting of
a one piece tubular member with flanges de- 20
pending therefrom to receive the runner
and with a hollow boss integral therewith
on its upper side, and elongated lengthwise
of the tubular member, said boss presenting
25 parallel side walls substantially in the plane
of the sides of the tubular member and end
walls curved on arcs struck from within
the boss, a plate having a depending flange,
and a coupling or post of general elliptical
30 cross sectional form and flared at top and
bottom, said post receiving within its upper
and lower end the flange of the plate and
the hollow boss and brazed thereto, substan-
tially as described.

2. A skate comprising a tubular member
35 having integral depending flanges to receive
the runner and having an integral hollow
boss on its upper side, a plate having a de-
pending flange and a hollow post connect-
ing the flange and hollow boss, said post
40 being flattened laterally and having curved
front and rear walls diverging from the
middle portion upwardly and downwardly,
substantially as described.

3. A skate comprising a tubular member
45 having integral depending flanges to receive
the runner and having an integral hollow
boss on its upper side, and elongated in the
longitudinal direction of the tubular mem-
ber, a plate having a depending flange, and
50 a hollow post having a cross sectional shape
elongated in the longitudinal direction of
the tubular body and flared upwardly and
downwardly in said longitudinal direction

and secured to the plate flange and boss,
substantially as described. 55

4. A skate having a tubular body with
integral hollow bosses extending up there-
from, plates for the heel and toe and posts
between said hollow bosses and the said
plates, said hollow bosses and posts being 60
elongated in the lengthwise direction of the
skate and having their sides parallel and
substantially in the planes of the sides of
the tubular body, substantially as described.

5. A skate having its body consisting of 65
a one-piece tubular member with depending
flanges, a runner held thereby, a foot plate,
a post for supporting the foot plate from
the tubular body and having its walls ex-
tending upwardly substantially in the plane 70
of the sides of the tubular body, said tubu-
lar body having an upwardly extending
portion engaging and holding the post, sub-
stantially as described.

6. A skate comprising a tubular member 75
with integral depending flanges, a runner
held thereby, a foot plate, a hollow post
having flattened sides and curved front and
rear walls, the sides of the post being sub-
stantially in the planes of the sides of the 80
tubular member, said tubular member hav-
ing means to hold the post, substantially as
described.

7. A skate comprising a tubular member
having depending flanges to receive the 85
runner, a foot plate, a hollow post having
substantially flat sides and rounded ends
which flare upwardly and downwardly,
said tubular member and foot plate having
90 means of connection with the post, substan-
tially as described.

8. In combination, a tubular member, a
runner attached thereto, a foot plate and a
supporting post between the foot plate and
tubular member, of substantially elliptical 95
form in cross section with its major axis ex-
tending in a direction longitudinally of the
skate, said post having substantially flat
sides approximately in the plane of the
sides of the tubular member, but flared lat- 100
erally at the upper portion, the front and
rear rounded portions of the post being
flared upwardly and downwardly in relation
to each other, substantially as described.

In testimony whereof, I affix my signature. 105
WILLIAM F. REACH.
